Fig. 3.

Fig. 4.

*Fig. 5.**Fig. 6.**Fig. 7.**Fig. 8.*FIG. 1 is a perspective view of a sign holder for use with acoustical dividers showing my new design, the sign and divider being shown in broken lines for illustrative purposes only;

FIG. 2 is a reduced perspective view thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a side elevational view thereof; and

FIG. 8 is a reduced perspective view of a second embodiment of the design of FIG. 1, the only difference residing in the lack of support means on the front portion.

I claim:

The ornamental design for a sign holder for use with acoustical dividers, as shown and described.
